(57) **CLAIM**

The ornamental design for a frame for fogger assembly, as shown and described.

DESCRIPTION

The frame for a fogger assembly is used to support the components of a fogger assembly used to dispense liquids as a mist or fog.

FIG. 1 is an isometric view of a frame for a fogger assembly showing my new design;

FIG. 2 is a front elevation view thereof, the rear elevation view being identical;

FIG. 3 is a right side elevation view thereof the left side elevation being identical;

FIG. 4 is a top plan view thereof; and,

FIG. 5 is a bottom plan view thereof.
